CLAIM

The ornamental design for a poultry feeder pan with a pivotable drop down center cone, as shown and described.

DESCRIPTION

FIG. 1 is a perspective view of a poultry feeder pan with a pivotable drop down center cone;

FIG. 2 is a top view thereof;

FIG. 3 is a side view thereof, the opposite side view being a mirror image;

FIG. 4 is a section view thereof, taken on line 4-4 of FIG. 2; and,

FIG. 5 is a section view, similar to FIG. 4, but with the pivotal center cone dropped down to remove excess feed.
